RIBBON WEAVE OR THE LIKE

Homer Lee Ballard, South Hill, Va., assignor to Burlington Industries, Inc., Greensboro, N.C., a corporation of Delaware

Filed Oct. 28, 1959, Ser. No. 849,266

5 Claims. (Cl. 139—383)

This invention relates to narrow woven fabrics, such as ribbons.

Ribbons, for example, so-called grosgrain ribbons, are conventionally provided with ornamental or decorative edges along either side thereof. In manufacturing grosgrain ribbons so that they will be provided with such ornamental or decorative edges, special weaving arrangements must be utilized as is understood. In the past such weaving arrangements allowed only a single weft thread to be passed through the fabric during each pass or pick of the traversing mechanism. The present invention is concerned with expediting the weaving operations in the manufacture of these ribbons.

Thus, it is an important object of the invention to provide a novel weaving arrangement particularly designed to facilitate the manufacture of ribbons, such as grosgrain ribbons, and characterized in that it permits a plurality of weft or filling threads to be woven into the fabric with each pass or pick of the traversing mechanism.

Another object resides in the provision of a novel method for producing attractive and ornamental edges in narrow woven fabrics, such as grosgrain ribbon, while allowing a pair of weft threads to be woven into the fabric with each pass or pick of the traversing mechanism.

Broadly stated, the present invention, as applied to a narrow fabric of interwoven warp and weft threads comprises: a central portion of plain weave; relatively narrow edges on either side of said central portion and including an open tape weave portion; a binder weave portion between said central portion and each of said edges; two weft threads being arranged in each shed in said central plain weave portion, and four weft threads being arranged in each shed in said binder and open tape weave portions. Further objects and advantages of the invention will be in part obvious and in part pointed out hereinafter.

The novel features of the invention may best be made clear from the following description and accompanying drawings in which:

Figure 1 is a schematic and fragmentary plan view of a narrow woven fabric, such as grosgrain ribbon;

Figure 2 is a greatly enlarged plan view of a portion of an edge of a conventional grosgrain ribbon, for example, as embraced by the dotted lines in Figure 1, and illustrating a known weaving arrangement;

Figure 3 is a view corresponding to Figure 2 but of a ribbon embodying the present invention, and showing the manner in which the weaving pattern is repeated.

Referring to Figures 1 and 2, conventional grosgrain ribbon includes a main or central portion and an ornamental or decorative edge along each side thereof. The ribbon is designated in Figure 1 by numeral 20, the central portion by numeral 22, and the edge portions by numeral 24. The warp threads in the ribbon are designated by the letter W while the weft or filling threads are designated by the letter F.

Figure 2 shows the weaving arrangement and the manner in which it repeats along one edge 24 of the ribbon,

2

it being understood that a similar weaving arrangement will be utilized along the other edge.

The central portion 22 normally is characterized by a plain weave which, as shown in Figure 2, comprises a pair of weft threads F arranged in each shed formed by the warp threads W. The edge 24 of conventional grosgrain ribbon includes an open tape or tube weave portion, and a binder weave portion is interposed between the central portion 22 and the edge portions 24.

The binder weave is shown in Figure 2 as including two warp threads 26, 28, with a pair of weft threads F passing through each shed formed thereby. It will be noted that the sheds formed in the binder weave portion are staggered with respect to the sheds formed in the central plain weave portion 22, whereby the two weft threads F in each shed in the central plain weave portion will pass through different sheds in the binder weave portion.

The open tape or tube weave portion 24 of conventional grosgrain ribbon is shown in Figure 2 as including a plurality of warp threads 30—41. The first warp thread 30 and the other even numbered warp threads in this portion 24 are shown as passing under three successive weft threads F, then over the next warp thread, then under the next three warp threads, then over the next warp thread, and so on. The odd numbered warp threads in the edge 24 are shown as passing under one weft thread, then over the next three weft threads, then under one weft thread, then over the next three weft threads, and so on.

To achieve the desired ornamental effect along the edges 24 in conventional grosgrain ribbon, a weaving arrangement such as that just described has been utilized. With such an arrangement, it is not possible to weave more than one weft thread F into the fabric at a time. In other words, to weave all of the sixteen weft threads F shown in Figure 2 into the fabric, there must be sixteen separate passes or picks, as is understood, and as should be evident from the drawing. Thus, it is necessary for there to be a separate pick for each of the weft threads F in a conventional grosgrain ribbon.

As has been discussed hereinabove, the present invention provides a novel arrangement and method whereby the time necessary for weaving narrow fabrics such as grosgrain ribbon, having ornamental edges, will be greatly reduced. In accordance with the present invention, a novel weaving arrangement is utilized for the edge or open tape weave portions and the binder portions whereby two weft or filling threads may be woven into the fabric on each pick or pass of the traversing mechanism.

Figure 3 illustrates a part of a grosgrain ribbon embodying the invention, and in a view corresponding to the view shown in Figure 2 of a conventional grosgrain ribbon. For the sake of consistency, and to facilitate comparison between the two, similar elements have been identified in Figures 2 and 3 by similar reference numerals.

Referring to Figure 3, it will be seen that, in the illustrative embodiment of the present invention, the binder weave portion comprises two warp threads 26', 28', while the open tape weave portion constituting the edge 24' is shown as comprising twelve warp threads 30'—41', thread 41' being used as a catch cord.

As in the conventional ribbon, the central portion 22' is shown as including warp threads W' arranged with two weft or filling threads F' in each shed formed between the warp threads. However, in the binder and open weave portions, there are four filling threads F' in each shed, with the sheds in the open tape weave portion 24' being staggered relative to the sheds in the binder weave portion so that two of the four filling threads F' in any shed in the binder weave portion pass through one shed in the open tape weave portion, while the other two filling

threads in the same shed in the binder weave portion pass through a different shed in the open tape weave portion. The warp threads in the binder weave portion preferably are arranged so as to form the desired sheds in the manner indicated in the drawing.

Considering the first pick identified by numeral 1 in Figure 3, it will be seen that two weft or filling threads F' are passed simultaneously through the sheds in the central portion 22', and then through the sheds in the binder weave portion and the open tape weave portion 24'. These threads F' then pass over the catch-cord 41' as shown. The sheds in the central portion 22' and in the binder weave portion are then changed, while the sheds in the open tape weave portion 24' remain the same, whereupon the same two filling threads are shown as passing under the catch cord 41' through the same shed in the open tape weave portion 24' through the newly formed shed in the binder weave portion and through the newly formed shed in the body or central portion 22', after which they will pass through a similar binder weave portion and open tape weave portion along the opposite side of the ribbon. This will constitute pick No. 2, as shown in the drawing. For pick No. 3, the sheds in the body or central portion 22', and in the open tape weave portions 24' will be changed, while the shed in the binder weave portions remains the same. Pick No. 3 will then be effected, and the subsequent picks, identified by numerals 4-8 in Figure 3, will take place with the sheds in the various portions of the ribbon being changed in this same pattern, as should be evident from the drawing. The entire ribbon will be woven in this manner.

As indicated, the binder weave portion and the open tape weave portion 24' of ribbon 20' will be of the same design and characteristics on both sides of the ribbon. Thus, it is believed that the foregoing detailed description of one edge of the ribbon should be sufficient.

It will be evident that by reason of the novel weaving arrangement of the present invention, the time necessary for weaving grosgrain ribbon, having desired ornamental or attractive edges along both sides thereof, will be greatly minimized, thereby enabling the ribbon to be produced faster and at less expense.

It has been found that the binder and open tape weave portions on the ribbon 20' of the present invention provide a satisfactory and acceptable appearance and one somewhat similar to the ornamental or decorative appearance of the corresponding portions on the conventional grosgrain ribbon, for example, as shown in Figure 2.

The present invention will thus be seen to completely and effectively accomplish the objects enumerated hereinabove. It will be realized, however, that various changes and substitutions may be made to the specific embodiment disclosed herein for the purpose of illustrating the principles of this invention, without departing from these principles. Therefore, this invention includes all modifications encompassed within the spirit and scope of the following claims.

What is claimed is:

1. A narrow fabric of interwoven warp and weft threads comprising: a central portion of plain weave; relatively narrow edges on either side of said central portion and including an open tape weave portion; a binder weave portion between said central portion and each of said edges; two weft threads being arranged in each shed in said central plain weave portion, and four weft threads being arranged in each shed in said binder and open tape weave portions.
- 10 2. The fabric described in claim 1 in which the sheds in said open tape weave portion are staggered with respect to the sheds in said binder weave portion whereby two of the four weft threads in a shed in said binder weave portion pass through one adjacent shed, formed by two warp threads in said open tape weave portion, while the other two weft threads in the same shed in said binder weave portion pass through another adjacent shed formed by the same two warp threads in said open tape weave portion.
- 15 3. The fabric defined in claim 1 wherein the number of warp threads in said open tape weave portion is greater than the number in said binder weave portion.
- 20 4. A narrow fabric ribbon or the like of interwoven warp and weft threads comprising a central portion of plain weave, a relatively narrow edge on either side of said central portion and including an open tape weave portion, a binder weave portion between said open tape weave portion and said central portion, a catch cord adjacent the free edge of said open tape weave portion along either edge of said ribbon, the weft threads being arranged in pairs in each shed in said plain weave portion and two pairs of said weft threads being arranged in each shed in said binder and open tape weave portions, and the weft threads alternately and in pairs passing over and under said catch cords along either edge of said ribbon.
- 25 5. The method of weaving a narrow fabric ribbon or the like having a central plain weave portion, narrow edges including an open tape weave portion, and a binder weave portion between said central plain weave portion and said open tape weave portion, said method comprising the steps of: providing sheds in each of said portions; passing a pair of weft threads simultaneously through said sheds; changing the sheds in said binder weave portion and said central plain weave portion but not in said open tape weave portion; passing said pair of weft threads simultaneously through the sheds in all of said portions; changing the sheds in said central plain weave portion and said open tape weave portion but not in said binder weave portion; simultaneously passing said pair of weft threads through said sheds in all of said portions; changing the sheds in said central plain weave portion and said binder weave portion but not in said open tape weave portion; and simultaneously passing said pair of weft threads through said sheds in all of said portions.
